ENCLOSED GAME WITH ROLLABLE
GAME PIECE

John A. Yerkes, New York, N. Y.

Application September 20, 1949, Serial No. 116,659

9 Claims. (Cl. 273—120)

1

This invention relates to games or game apparatus and particularly to games of convenient pocket size, although, it is suitable for larger sizes.

One of the objects of the invention is to provide a relatively inexpensive and novel game device.

One of the features of the invention is that it can be economically constructed and adapted to simulate numerous card games, dice, roulette, number combinations, color combinations, etc.

One of the features of the invention is a fully enclosed construction arranged so that the balls or playing pieces cannot be lost. In addition to preventing loss, a further advantage of a fully enclosed game of this type is that the balls may be of relatively small size. When a ball playing piece must be grasped by the hand to play the game, the ball must be of substantial size and the size of the device increased accordingly. Upon such an increase in size, the construction becomes more expensive and frequently is not convenient for carrying in the pocket.

Another advantage of the invention is that the simple act of inverting or tilting the device will restore the ball or balls to a play-starting position. Thereafter, the act of returning the device to a substantially upright position automatically puts the balls into play, although, as will be explained hereafter, other means may be used to put the balls into play. Once a ball is in play, chance alone controls the pocket into which the ball rolls, provision being made in the device to prevent affecting the course of the ball by manipulation or skill of the player in operating the game.

In one aspect of the invention, an enclosed game is used having a starting chamber connected to the playing chamber, the playing chamber having a multiplicity of pockets with suitable indicia associated therewith. There is an opening between the starting chamber and the playing chamber through which the ball or balls can pass. When the device is turned upside down, the balls will pass from the playing chamber through said aperture into the starting chamber. Upon again turning the game to its upright position, the ball or balls will roll out of the starting chamber through the opening into the playing chamber and will roll into one of the pockets. Means are provided in the structure to make the game controlled alone by chance and to facilitate movement of the ball or balls from the playing chamber into the starting chamber.

Another feature of the invention is found in 55

2

one embodiment useful in the game of draw poker or the like. In such an arrangement, means can be provided so that selected balls may be retained in their pockets after the first time the game has been played and the "discards" re-played as in draw poker. Such can be accomplished without manually touching the balls. In an alternative form, a valve arrangement can be employed to put into play a single ball at a time so that games such as stud poker may be played.

In card games in which several players simultaneously play, as in various hands of poker, and in which each player conceals his hand, the present device is particularly suited to such concealment because of its small size, each player using his own device and displaying his hand after completion of play.

In one form of the invention, as in a simulated poker game type wherein 5 balls are used, 1 ball can be colored differently than the other 4 so that games can be played requiring only 1 ball. Examples of such games are high-card, cut, showdown, or establishing a trump or "point" as in gin-rummy, etc.

Another advantage of the invention is that the present device enables convenient play in windy outdoor places and on small surfaces. Also, rapid play is facilitated because a ball in play promptly seeks and rests in the pocket in contrast to the spinning disc type, such as roulette, or other long rolling or agitating devices.

Transparent plastic or similar material may be used for the casing so that there is full visibility from all angles. Also, suitable advertising or printing may be placed on the device. The various surfaces in the device can be given suitable angles so as to produce the desired results as will appear hereafter.

These and other advantages, objects, and features of the invention will become apparent from the following description and drawings which are merely exemplary.

Figure 1 is a plan view of one form of the device especially adapted for the playing of certain card games, a portion of the transparent cover being broken away.

Figure 2 is a section taken along the line 2—2 of Figure 1.

Figure 3 is a plan view of another form of the device adapted for use in simulating play with dice, there being 12 pockets and 2 balls.

Figure 4 is a sectional view taken along the line 4—4 of Figure 3 with a portion of the base unbroken.

Figure 5 is a plan view of another form of dice

game having 2 joined devices of 6 pockets each and 1 ball for each.

Figure 6 is a section taken along the line 6—6 of Figure 5.

Figure 7 shows 5 balls, one of which is colored differently from the other 4, which can be used in a device constructed according to Figures 1 and 2.

Figure 8 shows a tapered pin which may be used in the device of Figures 1 and 2.

Figure 8A is a top view of Figure 8.

Figure 9 is a plan view of another form of dice game or the like, having 6 pockets capable of accommodating 2 balls each, 2 balls being used in the game.

Figure 10 is a fragmentary plan view of still another form of dice game or the like, in which a single ball is used and there are 36 pockets, one for each possible combination of the dice.

Figure 11 is a fragmentary view of a so-called bar-bell game in which 3 balls preferably are used and the object is to obtain pairs or threes of similar pockets.

Figure 12 is a fragmentary view of a roulette type game in which there are 38 pockets and a single ball is used.

Figure 13 is an inverted sectional view diagrammatically showing the device illustrated in Figure 4 and depicting the path of the balls returning to the starting chamber.

Figures 14, 15, 16, 17 and 20 are diagrammatic views which by omitting, displacing, or modifying important elements in the construction, serve to illustrate the value of various features relating to the construction described herein.

Figure 18 is a diagrammatic sectional view of a modified form of the invention wherein a valve arrangement is employed.

Figure 19 is a sectional view taken along the line 19—19 of Figure 18.

For purposes of simplification and clarity, similar parts will be identified by the same numerals in each of the figures, using appended letters with the numerals to distinguish parts in one figure from similar parts in another.

Referring to Figures 1 and 2 specifically, and generally to the other figures, a preferably opaque, plastic base 1 is provided with a multiplicity of pockets 6 near its outer periphery. Dividing walls 8 preferably are rounded or beveled on their top surfaces so that a ball will not lodge on top of the wall but will be induced to fall into said pockets. Where it is convenient to space the pockets relatively widely apart, such as in Figures 3 and 4, for example, pockets 6A are separated by substantial dividing elements having an upper ridge 10A and sloping surfaces 9A. Referring again specifically to Figures 1 and 2, the upper surface of said base preferably is formed to provide a sloping conical raceway 3, thus giving a surface on which a ball will not tarry but will roll toward and into one of said pockets 6. Near the apex of said raceway, another cone 4 is formed, having a more acute angle, extending substantially upward and culminating in an apex 5 which is slightly rounded at its tip for a reason described hereafter.

Where better visibility or convenience requires it, base 1 may be provided with an annular inwardly sloping surface 11 (Figs. 1 and 2). For maximum economy of size, surface 11 may be omitted as shown in the other figures.

A transparent cover 2 preferably is molded of

clear plastic. It may be secured to said base in any suitable manner such as by cementing at 7, said cover being preferably generally conical in form with cylindrical portions at the top and bottom as shown. The inside conical surfaces of said cover provide a return course for a playing ball 19 when the device is inverted so that the ball will return to a starting chamber 25 through a hole 14 near the upper end of said cover 2.

A transparent plastic cap 16 may be secured to said cover by any suitable means such as by cementing at 17. The upper end of said cover 2 may serve as the floor 15 of said chamber and is preferably obtusely conical in form with the angle of slope of said floor very small for reasons which will be explained later. The upper wall 18 of said cap 16 may be conical in form as will be explained later.

Near the upper end of the cover are a number of ribs 13 which are preferably arranged in a pattern as shown in Figure 1. The important purpose of these ribs is to prevent time-consuming whirling of the ball or balls, when the device is inverted and the balls are to be returned to the starting chamber 25. Models of the present device without said ribs 13 or equivalent were found to be unsatisfactory because of the time lost as the balls whirled in generally circular paths near hole 14 or in a rocking fashion, jumping repeatedly over said hole. While said ribs may be of the form shown in the left side of Figures 5 and 6 and which prevent the whirling action mentioned, the latter form is not as satisfactory as that shown in Figures 1 and 2 in which, besides arresting the whirling action, the rocking is also prevented because a ball which "jumps" hole 14 strikes another rib on the other side of the hole and is promptly returned. The configuration and arrangement of the latter ribs also are of advantage in that no matter from which direction a ball strikes a rib, it will be deflected toward hole 14. In practice, the balls enter chamber 25 almost instantly, and even when inversion is not complete. It will of course be understood that depressed grooves may be substituted for the raised ribs 13.

For purposes of clarity alone, ribs 13 have been omitted from many of the figures but it is to be understood that their use is preferred.

On the upper surface of conical raceway 3 and adjacent pockets 6, indicia 24, one for each pocket are provided. These may be inscribed in any suitable manner as by integral molding, by printing, etc. These indicia may be of many forms and shapes, a number of which are shown in the various figures, such depending on the particular game.

Referring especially to Figures 1, 2, 7, and 8, transparent cover 2 may be provided with a multiplicity of small, slightly conical holes 21, one for each pocket 6 in base 1. To assure that said holes 21 will be aligned perfectly above the centers of said pockets 6, a depending lip 20 in cover 2 (Fig. 2) is arranged to fit into a mating slot in base 1, so that, in assembly, said cover is correctly oriented with said base and with said holes 21 centrally aligned with said pockets 6. Small tapered pins 22 are formed so that they will fit tightly into holes 21 and will not come loose unless manually loosened. As shown at the left in Figure 2, the lower end of said pins extends nearly to a ball 19 in a pocket 6 so that

although the entire device is inverted, said ball is prevented from emerging from said pocket.

Holes 21 and pins 22 are not essential to the operation of the device but are of the essence in providing novel means to play games such as draw poker. By using indicia such as are illustrated in Figure 1 with 5 balls, and using 4 pins such as the one illustrated in Figure 8, such games may be simulated. Thus, after playing the 5 balls initially, barring a "pat" hand in which no further "draw" is made, up to four of said balls may be "pinned-down" so to speak and the remainder replayed or "drawn." For convenience in shipping or safe carrying in the pocket four holes 23 (Fig. 2) may be provided, preferably near the shelter of cap 16.

As shown in Figure 7, in games such as poker in which five balls are used, or in any game using a multiplicity of balls, one of the balls 19N may be colored differently than the other balls. For example, four balls 19 may be white or natural steel color while one ball 19N may be gold plated or red. Thus, while the game normally requires a multiplicity of balls, it may also be used for purposes requiring one ball, by simply disregarding all but the red ball 19N. As stated above in the objects, such a ball may be used to simulate cutting the deck in games such as high-card, show-down, or to cut for trump or "point" in gin rummy and other games.

Referring specifically to Figure 1, attention is particularly directed to indicia 24, it being noted that playing cards are simulated and a full deck of 52 cards shown, although more or less cards may be used as desired. The novel arrangement of the cards merits note; as in a perfect shuffle (never attained in actual playing cards), the cards are distributed in accordance with their frequency of occurrence in the deck. Thus cards of the same suit, i. e. hearts, diamonds, spades, clubs, are exactly four pockets apart; cards of like numerical values, i. e. aces, deuces, treys etc., are exactly thirteen pockets apart; sequences, i. e. consecutive cards such as 3, 4, 5, 6 etc., are broken up with the components 4 pockets apart. Such distribution is essential in a game of chance. Numerous other arrangements are, of course, possible.

Referring particularly to Figures 3 and 4, these figures illustrate a novel application of the invention in which the play is based on the sum of the values of any two pockets in a duplicated series of indicia. Specifically these figures show a game simulating dice but with the "odds" slightly modified.

Figures 5 and 6 illustrate a unique game device similar to dice in that the score of each throw equals the sum of the values of the pocketed balls. This novel device uses two balls, one for each of the indicia 24B and 24C and two complete units are tied together to form an integral unit. Bases 1B and 1C are molded as one unit, being joined as at 27 and transparent covers 2B and 2C are integrally molded, being joined as by web 26. In this form of the device, the "odds" in such games as dice, illustrated, are in no way modified from the actual game and it is felt to be an attractive and novel embodiment. Being separated, two balls never seek the same pocket and pile up.

Figure 9 is a plan view of a novel game in which, by using multiple pockets and multiple balls with a single series of indicia, the playing of a game normally requiring multiple indicia is enabled. In the form illustrated, two balls

are used and the pockets are capable of receiving both balls. A dice game is thus simulated, with a single dice (or indicia) series, the sum of the pocket values being added for scoring, the "odds" of ordinary dice not being changed. Minimum size is one of the advantages of this arrangement.

Figure 10 is a fragmentary plan view of a novel game in which all the possible combinations of two or more series of indicia are used, one combination per pocket. A single ball thus serves to yield all the scores attainable. In the specific form shown, for dice, the two series normally on a pair of dice are combined in the 36 possible combinations, one for each pocket. Such a single ball game has the obvious advantage of enabling the players' attention to be focused on one ball only.

Figure 11 is a fragmentary plan view illustrating a novel game in which multiple balls are used (as in the card game illustrated in Figure 1). In this instance, three balls are used to simulate a game in which the familiar indicia 24K including "bars," "bells," and other shapes are used and in which pairs and threes determine the value of the score. Thus, in the illustration a pair of "bars" is shown scored. It should be obvious from this illustration that any arrangement of indicia is possible; with less frequent inclusion of the symbols which merit higher arbitrary awards. Thus, as in the actual machine game involved, "bars" occur least frequently, then come "bells," "plums," "oranges," "cherries" and "lemons" in ascending order of frequency. This figure illustrates how large a variety of games may be adapted to the present device in which colors, denominations or any other arbitrary values may be used. It should also be understood that any practical number of balls may be used, and said balls may be in a variety of colors to suit the requirements of the game.

Figure 12 is a fragmentary plan view of a novel single-ball game in which the well-known game of roulette is simulated. Pockets 6L, identified by indicia 24L marked "0," "00" and 1 to 36, are used. Thus is produced a most convenient inexpensive and compact game simulating roulette, not requiring skillful manipulation of the ball, with no danger of loss of the ball and without the tedious delays caused by a whirling ball or spinning disc.

Operation

The discussion which follows relates generally to all the figures with the exception of Figure 19 which will be discussed later.

Play is started with the ball or balls in starting chamber 25 with the device positioned substantially level and upright as in Figure 2, 4 or 6. The ball or balls drop through hole 14, strike apex 5 of cone 4, roll down raceway 3 and into a pocket or pockets 6. To return the ball or balls to chamber 25, the device is at least partially inverted. The ball or balls will drop out of pockets 6 and onto the conical surface of transparent cover 2, then roll downwardly to and through hole 14 and into chamber 25.

This extremely simple operation was not, however, easily achieved in practice in numerous models, as the following will fully explain, keeping in mind that it is an important object of this invention to avoid unduly influencing the course of the balls either by skill or manipulation by the player or by structural defects in design.

Considering first the structure of chamber 25,

it should be noted that the floor 15 of said chamber is slightly conical in form with a gentle slope toward hole 14. The value of this construction will be evident by inspection of Figure 14. In that figure, chamber 25E has no floor. Assume that a ball has been deposited in said chamber by inverting the device and the player starts to turn the device toward erect position. Long before this can be done, as clearly shown in the figure, the ball will roll out of the chamber and will then invariably roll to one side as shown in dotted outline and by arrows, and if several balls are used, all will pile up to one side so that such a game would be worthless. The necessity for a floor 15, was thus clearly established.

As to the gentle slope of floor 15, it should be clear from Figure 20 that even though a floor be used having a central hole 14F, if the slope of the floor were steep, the balls would roll into and through hole 14P long before the device approaches an erect position so that the identical defect shown in Figure 14 would exist and balls would seek pockets on the low-tilted side of the game.

In practice, it has been found desirable to slope said floor 15 a matter of only two or three degrees. Thus, when the device is held or set erect on any substantially level surface, the balls will gravitate to hole 14, but not normally until then. In practice, the balls tend to nestle against the side walls of cap 16 and await turning to erect position of the device before gravitating toward hole 14. To encourage the balls to move promptly toward said side walls when chamber 25 is being recharged, the upper surfaces 18 of cap 16 are substantially conically sloped. When reloading a multiplicity of balls, this construction is especially useful (Fig. 13), as the balls in the chamber move laterally and leave the area of hole 14 unobstructed.

Considering further the construction and purpose of hole 14, it should be carefully noted that said hole is preferably only slightly larger than the ball because as Figure 15 shows, even though the other elements of construction are present, a hole 14F which is too large will permit the balls to drop to one side and even the slightest tendency of the ball to fall to one side of center causes repeated seeking of one side and defeats the objects of the game. It is thus clear that, for impartial, or chance distribution, hole 14F is preferably located centrally with respect to the pockets and other elements and should also be only slightly larger than the ball.

It should be noted that hole 14 is preferably cylindrical in form, the tubular side walls serving to kill any lateral momentum which the ball acquires in rolling down the slope of floor 15. As shown in Figure 17 if an otherwise properly designed game were equipped with a hole 14H having the form of a "knife-edge" orifice with sharp edges 29, the ball would be more likely to repeatedly roll as shown in dotted outline, i. e. to one side. Since there must be at least some clearance between hole and ball, the ball may miss striking knife edge 29 entirely.

This is much less likely to happen in the preferred cylindrical orifice 14.

When the ball is put into play, it will drop a short distance and will strike apex 5 of cone 4 after it emerges from hole 14. It is important to note that said apex 5 is located very close to hole 14, and this distance should be so close that there is little more room than that needed for the ball to clear. The reasons for this construc-

tion will be clear from inspection of Figure 16. In early models made of the present device with the cone apex 5G located a substantial distance below hole 14G, the balls tended strongly to roll to one side unless the game was positioned perfectly level with great accuracy. The figure illustrates what occurred with great frequency on a surface sloping at an angle of only one degree. As shown in dotted outline, gravity influenced the balls to strike apex 5G slightly off-center, so as to cause the undesirable results mentioned.

By positioning the apex 5 of cone 4 close to hole 14 as described, the influence of gravity is not sufficient to affect the course of the balls even when the game is not held perfectly level. The balls strike apex 5 after falling a minimum distance, rebound and fall in any direction with equal probability.

Of course, it is possible for the player to defeat 20 the purpose of gently sloping floor 15 of chamber 25, by violently agitating the device if all players agree, when not nearly level, and cause the balls to drop through hole 14, or when a fairly level surface is not available, as on the beach sands. 25 Even in these cases, it will be found that chance alone controls the course of the balls and manual control is substantially not possible.

The path of the played ball after leaving cone 4 is generally radially down the slopes of conical 30 raceway 3 to pockets 6. Obviously, to preserve an equal chance for all pockets, cone 4 is centrally located, as is hole 14, pockets 6 being equidistant from hole 14.

It should be noted that conical raceway 3 preferably is slightly sloped so that the rolling of the balls will be slowed only slightly and may easily be followed by the eye. Printing on such a surface is also more practical than on a steeper slope. It should be noted that an alternate construction, 40 such as shown in dotted lines in the right half of Figure 6, may be used, in which apex 5C is formed more directly by more-steeply sloped raceway 36.

The apex 5 of cone 4 is rounded slightly, this 45 form of target for the balls being found to give excellent distribution, whereas flat, large round, and many other forms of surfaces failed to give consistently good results.

When a play has been made and it is desired 50 to return one or more balls to the starting chamber, the game may be inverted (Fig. 13) and the balls permitted to roll into chamber 25D, anti-whirl ribs 13 or the like (Fig. 1) having been fully explained. It is of importance to note that it is unnecessary to completely invert the device 55 to restore the balls to said starting chamber. The conically sloping walls of cover 2 are relatively steeply sloped. Obviously, complete inversion is unnecessary and it is deemed within the scope of the invention to design the device so that it may 60 be tilted any convenient amount to facilitate re-entry of the balls into the starting chamber. I have found in the present embodiment that around twelve to fourteen degrees is a convenient slope for the walls of cover 2 to insure speedy 65 return of the balls without inordinately great height, so that the device may conveniently be carried in the pocket, although the angle may be varied therefrom.

Since a relatively inexpensive device such as 70 this lends itself for use for advertising gifts, means enabling an advertising imprint can be provided. While such advertising matter may be imprinted, for example, on raceway 3 near cone 4, the space is not large and, often, advertisers 75 prefer to imprint an inconspicuous area, not nor-

mally visible, yet hoping that the advertisement will be seen occasionally. Referring to the left half of Figure 6, a convenient place is provided for pasting-on a circular cardboard label 12. Not only is such a label amply large and normally hidden but there is assurance that the label will be exposed and readable with every play.

A novel modification is shown diagrammatically in Figures 18 and 19. It should be understood that structurally from hole 14M downward, this modification embodies all the features discussed above and pertaining to the other figures. Chamber 25M is essentially as previously described, however the floor 15M may be relatively steeply sloped. An elongated neck 36A on top of cover 2M is provided with a suitable valve structure whose purpose is to enable the player to put one ball at a time into play, playing successively any number of balls. Such a structure will be found useful in certain games such as simulated stud poker in which one card at a time may be played.

The valve structure shown consists of 2 flat plates 30 and 32 which may be separate or a single plate bent back on itself as shown and with the open ends secured together by any suitable means such as plate 31 and rivets 33. Said plates fit snugly in a pair of spaced slots in neck 36A which intersect hole 14M. A hole 34 in upper plate 30 and a hole 35 in lower plate 32 are relatively staggered laterally so that only one or the other hole may be placed in register with hole 14M. Thus, when the valve plates are moved to the right as shown in the figure, a single ball will drop through hole 34 and stop on plate 32. When the plates are shifted to the left until hole 35 in lower plate 32 is in register with hole 14M, the ball will drop through and into play. Repeating the above operation will feed one ball at a time into the playing area. With the valve as shown, when it is desired to return the balls to chamber 25M, the game is inverted as usual, and the valve slides are rapidly reciprocated admitting a ball to said chamber with each reciprocation cycle. It is understood that slide plates 30 and 32 may be equipped with an additional aligned pair of holes, which, when registered with hole 14M as by shifting the valve structure an unusually large distance, will permit rapid play of all the balls and/or unhampered return of the played balls. Various other types of valve structures can be used, such as a rotary valve.

While the preferred embodiment is a game of chance, it is deemed within the scope of this invention to employ the above-described device for games requiring some elements of skill, as in games where it is permissible to attempt to influence the course of the game piece toward certain pockets, by tilting or jarring the device.

It is to be understood that variations can be made in the described details of construction without departing from the spirit of the invention except as defined in the appended claims.

What is claimed is:

1. In a fully enclosed game, the combination including an enclosed ball reservoir having a floor, a playing chamber having sloping playing surfaces, there being a hole in said floor connecting said reservoir and playing chamber, a playing ball, a plurality of pockets in said playing chamber, said playing surface sloping generally toward said pockets, playing indicia adjacent said pockets, and a non-playing sloping surface in said chamber sloping generally toward said hole

when the game is in inverted position for guiding said playing ball toward said hole and reservoir.

2. In an enclosed game having a plurality of pockets, the combination including an upper enclosed ball reservoir having an approximately level floor, a lower playing chamber having a playing floor sloping toward said plurality of pockets, there being a ball passage in said reservoir floor connecting said reservoir with said playing chamber, a playing ball, and a ball return surface in said chamber located above said playing floor and sloping toward said ball passage when the game is in inverted position.

3. In an enclosed game, the combination including an upper enclosed ball reservoir having an approximately level floor, a lower playing chamber having a playing floor sloping toward a plurality of pockets, there being a ball passage in said reservoir floor connecting said reservoir with said playing chamber and located substantially equidistant from said pockets, a playing ball, and a ball return surface in said chamber located above said playing floor and sloping toward said ball passage when said game is inverted for guiding a ball to said reservoir upon inversion of said game.

4. In an enclosed game device, the combination including a game piece, an enclosed reservoir adapted to receive said game piece before the game piece is put into play, sloping surfaces adjacent to and converging toward said reservoir for returning the game piece by gravity to said reservoir when the device is inverted from its normal upright position, an enclosed chamber having game piece receiving pockets therein, there being a game piece passage between said reservoir and said chamber receiving said game piece from said sloping surfaces converging toward said reservoir, and sloping surfaces leading toward said pockets so as to guide said game piece thereto after the game piece passes from said reservoir to said playing chamber.

5. In an enclosed game device, the combination including an enclosed starting chamber, a playing chamber having a plurality of pockets with playing indicia adjacent thereto, said playing chamber and starting chamber having a connecting opening therebetween, a rollable game piece, said game piece being transferable between said chambers through said opening, and a central pointed portion extending upwardly in said playing chamber under said connecting opening and closely spaced thereto, said spacing being a distance slightly greater than the diameter of the game piece.

6. In an enclosed game device, the combination including a rollable game piece, a reservoir adapted to receive said game piece before the game piece is put into play, sloping surfaces adjacent to and converging toward said reservoir for returning the game piece by gravity when the device is inverted from its normal upright position, said sloping surface having game piece anti-whirl means thereon restricting circular motion of said game piece about the axis of said device, a playing chamber having game piece receiving pockets therein, there being a connecting passage between said reservoir and chamber through which said game piece can pass, said sloping surfaces leading to said connecting passage and sloping surfaces leading toward said pockets to guide said game piece thereto after the game piece passes from said reservoir, through said passage and into said chamber.

7. In an enclosed game device, a playing cham-

ber having a floor and a roof, a plurality of pockets around the periphery of the floor, said floor having a sloping surface leading to said pockets, said roof having a centrally located aperture therein, an enclosed starting chamber above said playing chamber roof connected to said aperture, said starting chamber having a sloping floor leading to said aperture, said playing chamber roof having a sloping surface converging and leading to said aperture, a ball, a conically shaped point extending upwardly from said playing chamber floor, said point being centrally located under said aperture so that a ball moving from said starting chamber through said aperture will contact said point and be rollably guided toward said sloping playing chamber floor to any one of said pockets.

8. An enclosed game device of claim 1 having a plurality of playing balls and including means selectively retaining playing balls in said pockets so that the game can be replayed with less than the original number of playing balls taking part.

9. An enclosed game device of claim 1 having

a plurality of playing balls and including a valve means controlling said hole admitting one ball at a time from said reservoir to said playing chamber.
